CONVEYOR SUPPORT CHANNEL

James Price Minns, Christies Beach, South Australia, Australia, assignor to Consolidated Standard Conveyor Systems Pty. Ltd., North Plympton, South Australia, Australia

Filed May 16, 1972, Ser. No. 253,918

Term of patent 14 years

Int. Cl. D12—99

U.S. Cl. D55—1 C

The figure is a perspective view of a conveyor support channel showing my new design with a portion broken away to indicate indeterminate length.

I claim:

The ornamental design for a conveyor support channel, as shown and described.
